UNITED STATES PATENT OFFICE.

JOSHUA R. HOUCHEIN, OF ATLANTA, GEORGIA, ASSIGNOR TO HOUCHEIN MANUFACTURING COMPANY, OF ATLANTA, GEORGIA, A CORPORATION OF GEORGIA.

PASTING-MACHINE.

No. 884,927.

Specification of Letters Patent.

Patented April 14, 1908.

Application filed February 15, 1907. Serial No. 357,516.

To all whom it may concern:

Be it known that I, JOSHUA R. HOUCHEIN, a citizen of the United States, and a resident of Atlanta, in the county of Fulton and State 5 of Georgia, have invented certain new and useful Improvements in Pasting-Machines, of which the following is a specification.

My invention relates to machines for applying paste, glue, gum, cement or other substances to paper articles, such as bags or sacks, and has for its object the improvement of devices of this character whereby the paste or other substance is applied to the required place, such, for instance, as the bottom fold of the bag, so as to secure the best results, and in such a way that it is not smeared over the outer side of the fold of the bag and the bag, as by the present method by external pressure.

20 To this end my invention consists of two rollers between which the bags are passed, one of which rollers is formed hollow, so as to hold the paste, and provided with a line of openings for its egress, said roller being connected with a hopper holding the paste by means of a tubular extension of the roller in which is mounted a screw or worm for feeding the paste into the roller.

30 The details of the construction and operation of my invention will be explained hereinafter, while the machine will be found illustrated in the accompanying drawing, which is a side view, partly in section, of my improved pasting machine.

35 In the drawing 1 indicates a suitable base on which are mounted the standards 2 and 3, in which are journaled rollers 4 and 5, simultaneously rotated by means of gear-pinions 6 and 7, respectively, keyed to or formed integral with the trunnions 8 of the rollers.

40 The upper roller 4 is formed hollow, as shown, and provided with a number of perforations 9, arranged longitudinally of the roller, while instead of a trunnion at one end it is provided with a tubular neck 10, journaled in journal-box 11.

45 The journal-box 11 is provided with an extension 12, on which is rigidly secured hopper 13, provided at its lower end with an opening 14, and surrounded by a stuffing-box 15 to receive the end of the tubular neck 10.

50 The arrangement of parts by which the journal-boxes of the upper roller may adjust themselves to varying thicknesses of ma-

terial will be obvious to any one skilled in mechanics and a specific construction by which this may be effected is thought to be unnecessary.

To insure feed of the paste through the neck 10 to the interior of roller 4, and to force it out of openings 9, I provide a screw or worm 16 in said neck 10, which extends into the lower end of hopper 13, with a stud-shaft extending from its end through a journal-box at one side of the hopper, with a pulley keyed thereto to receive a power-belt (not shown) for rotating the screw or worm.

It will be understood that the speed of the worm may be regulated to insure feeding 70 the proper amount of paste through openings 9 to adequately perform the work.

In operation, the hopper is filled with paste which is fed through neck 10 by means of screw or worm 16 into roller 4, from whence it passes through openings 9 onto the bag or other article that passes between the rollers 4 and 5.

It will be understood that the device above described may be operated as a separate machine by any suitable power or may be assembled with a bag-making machine of any form to which it may be adapted and I do not therefore confine myself to the construction shown and described except where 85 the hereinafter claims are specifically limited.

It will also be understood that instead of one tubular neck and hopper and worm two may be provided, one at each end of roller 4.

Having thus described my invention, what 90 I claim is—

1. A pasting machine comprising two complementary rolls provided with means to actuate them, one of said rolls being hollow and provided with perforations, said hollow roll having a tubular neck, a hopper suitably secured and provided with an opening to receive the free end of said tubular neck, and a worm mounted in said neck and hopper, substantially as shown and described.

2. A pasting machine comprising suitable standards, a roll journaled in said standards, another roll journaled in boxes mounted in said standards, the last mentioned roll being hollow and provided with perforations, a tubular neck extending from said roll and forming one of the trunnions of the roll, a hopper secured to the journal box in which is

mounted said tubular neck, said hopper being provided with an opening to receive the free end of said tubular neck, a worm mounted in said tubular neck and said hopper, and
5 a stud-shaft extending from said worm, and a power-pulley keyed to said shaft, substantially as shown and described.

In witness whereof, I have hereunto set my hand in presence of two subscribing witnesses.

JOSHUA R. HOUCHIN.
